TIRE FOR A VEHICLE WHEEL

David Michael Lamb, Sutton, England, assignor to
Dunlop Limited, London, England

Filed Aug. 21, 1972, Ser. No. 282,299

Claims priority, application Great Britain Sept. 4, 1972

Term of patent 14 years

Int. Cl. D12—15

U.S. Cl. D12—136

FIG. 1

FIG. 3

FIG. 2

FIG. 1 is a perspective view of the tire of my new design.

FIG. 2 is a fragmentary perspective view.

FIG. 3 is a fragmentary plan view.

It is to be understood that the tread pattern shown is continuous throughout the circumference of the tire.

I claim:

The ornamental design for a tire for a vehicle wheel, as shown and described.
